CLAIM

We claim the ornamental design for a volleyball, as shown and described.

DESCRIPTION

FIG. 1 is a front, top perspective view of a volleyball;

FIG. 2 is a front view of the volleyball of FIG. 1;

FIG. 3 is a rear view of the volleyball of FIG. 1;

FIG. 4 is the right side view of the volleyball;

FIG. 5 is the left side view of the volleyball;

FIG. 6 is the top view of the volleyball; and,

FIG. 7 is a bottom view of the volleyball.

The broken lines shown in the figures depict portions of the volleyball that form no part of the claimed design.
